Primary Examiner — Richard E Chilcot(74) *Attorney, Agent, or Firm* — Hooker & Habib, P.C.(57) **CLAIM**

The ornamental design of a combination bottle and pouch, as shown and described.

DESCRIPTION

FIG. 1 is a front view of the combination bottle and pouch showing our new design, the bottle body at one end of the combination, the closed cap dispenser and at the opposite end of the combination, the locking ring disposed between the cap dispenser and the bottle body, the pouch attached to the locking ring and disposed in the bottle body.

FIG. 2 is a front view of the bottle body, cap dispenser, and the locking ring and attached pouch separated apart from one another, the cap dispenser open with the lid of the cap dispenser swung away from the base of the cap dispenser.

FIG. 3 is similar to FIG. 2 but with the cap dispenser closed.

FIG. 4 is similar to FIG. 3 but with the locking ring that has two pouches attached thereto also attached to the closed cap.

FIG. 5 is similar to FIG. 4 but is a front-top perspective view. FIG. 6 is similar to FIG. 5 but with the cap dispenser/locking ring/pouch assembly laying on its side, the cap dispenser open; and,

FIG. 7 is similar to FIG. 6 but with the cap dispenser closed. No color is claimed as part of the design.
